CLAIM

We claim the ornamental design for bottle upper, as shown and described.

DESCRIPTION

FIG. 1 is a perspective front, top, right side view of the bottle upper showing our new design;

FIG. 2 is a perspective rear, top, left side view thereof;

FIG. 3 is a front view thereof;

FIG. 4 is a rear view thereof;

FIG. 5 is a left side view thereof; and,

FIG. 6 is a right side view thereof.

The broken line showing in FIGS. 1-6 is for illustrative purposes only and forms no part of the claimed design.
